UNITED STATES PATENT OFFICE.

JOSEPH SONNENBERG, OF ALIDA, MINNESOTA.

MOTOR-PROPELLED VEHICLE.

1,129,748.

Specification of Letters Patent.

Patented Feb. 23, 1915.

Application filed April 30, 1914. Serial No. 835,504.

To all whom it may concern:

Be it known that I, JOSEPH SONNENBERG, a citizen of the United States, residing at Alida, in the county of Clearwater and State of Minnesota, have invented a new and useful Motor-Propelled Vehicle, of which the following is a specification.

The invention relates to improvements in motor propelled sleighs.

10 The object of the present invention is to improve the construction of motor propelled sleighs and to provide a simple, efficient, and comparatively inexpensive self-propelled vehicle, of strong and durable construction, equipped with propelling mechanism adapted to operate effectively on loose wet snow as well as on packed snow.

20 A further object of the invention is to provide a motor propelled sleigh in which the propelling mechanism will be operable to make a quick short turn, whereby the sleigh may be easily guided with accuracy.

With these and other objects in view the invention consists in the construction and 25 novel combination of parts hereinafter fully described, illustrated in the accompanying drawing, and pointed out in the claims here-to appended, it being understood that various changes in the form, proportion, size 30 and minor details of construction, within the scope of the claims, may be resorted to without departing from the spirit or sacrificing any of the advantages of the invention.

35 In the drawing:—Figure 1 is a side elevation of a motor propelled sleigh constructed in accordance with this invention. Fig. 2 is a plan view of the same. Fig. 3 is a transverse sectional view on the line 3—3 of Fig. 2. Fig. 4 is a transverse sectional view on the line 4—4 of Fig. 2. Fig. 5 is a transverse sectional view on the line 5—5 of Fig. 2. Fig. 6 is a transverse sectional view of one side of the motor propelled sleigh on 45 the line 6—6 of Fig. 2. Fig. 7 is a horizontal sectional view on the line 7—7 of Fig. 1, illustrating the construction of the propelling mechanism. Fig. 8 is a transverse sectional view of the propelling mechanism, 50 taken on the line 8—8 of Fig. 1. Fig. 9 is a vertical sectional view illustrating the manner of connecting the rear runners to the rear bolster. Fig. 10 is a detail view of one

of the gears and the longitudinal lever of the steering mechanism. Fig. 11 is a detail 55 sectional view on the line 11—11 of Fig. 9. Fig. 12 is a longitudinal sectional view through the rear portion of the sleigh, illustrating the manner of mounting the bridle. Fig. 13 is a vertical sectional view on the 60 line 14—14 of Fig. 2.

Like numerals of reference designate corresponding parts in all the figures of the drawings.

In the accompanying drawings, in which 65 is illustrated the preferred embodiment of the invention, 1 designates a main frame designed to support a body 2 of the automobile type, as illustrated in dotted lines in Fig. 1 of the drawings, but any other preferred form of body to adapt the sleigh for various purposes may be employed. The 70 sleigh may be made of any desired size and it is equipped with front and rear runners 3 and 4, connected with front and rear bolsters 5 and 6 of the main or supporting frame of the sleigh. The front runners 3 are provided with centrally arranged vertically disposed pivots 7 mounted in suitable bearing openings 8 in the front bolster 75 and adapted to permit the front runners to be turned on independent axes for guiding the sleigh. The vertical pivots, which are 80 suitably secured in the said bearing openings of the bolster, have attaching portions 85 9 which are bifurcated to straddle upwardly projecting central portions 10 of the front runners. The front runners 3, which are curved longitudinally and which extend in advance and in rear of the bifurcated or 90 forked portions of the vertical pivots, may be constructed in any suitable manner and are preferably composed of a wooden body portion reinforced by an outer covering 95 of sheet steel or other suitable material. The rear runners are also designed to be 100 constructed and protected in a similar manner, whereby a sleigh of great strength and durability is provided.

The front runners are turned on their 100 pivots by steering mechanism comprising a vertical steering shaft 12 journaled in suitable bearings in the front bolster and a supporting bar 13, and provided at its upper end with a steering wheel 14 and keyed or 105 otherwise secured at its lower end to a hori-

zontal gear wheel 15. The gear wheel 15 meshes with an intermediate gear 16 of slightly less diameter than the gear 15, and in turn meshing with a still smaller gear or pinion 17. The supporting bar 13, which is designed to be constructed of suitable metal, is arranged in spaced relation with the lower face of the bolster, and it is provided at its terminal portions with right angle bends 5 which offset the body portion of the supporting bar from the bolster. The terminals of the supporting bar are bolted or otherwise secured to the bolster, and the gears 16 and 17 are mounted on stub shafts 18 and 19, 10 which are journaled in suitable bearings of the front bolster and the said bar 13. The gears 15, 16 and 17 form a set or train of gearing for oscillating the longitudinally disposed lever 20, centrally connected to the 15 gear or pinion 17, and bent at opposite sides of its center to arrange its terminal portions in the median plane of the sleigh when the front runners are in alinement with the rear runners. The number and size of the gears 20 for connecting the steering shaft with the lever 20 may be varied to suit the size and character of the sleigh to enable the front runners thereof to be easily turned on their pivots by the operator. The centrally arranged longitudinal lever is of a length substantially the same as the front and rear runners, and its terminals are connected with the ends of the front runners by front and rear rods 21 or other suitable connections. The rods 21, which are oppositely inclined, as clearly shown in Figs. 3 and 4 of the drawings, are provided at their terminals with eyes, which are linked into suitable eyes of the runners 3 and the lever 20. The 25 steering mechanism is adapted to coöperate with the propelling mechanism in the turning of the sleigh, as hereinafter fully described. No claim is made in the present application to the steering mechanism.

The rear runners are provided with centrally arranged upwardly projecting portions 22 having recesses 23 receiving reduced portions 24 of the rear bolster. The recesses 23 of the central portions of the 30 rear runners are metal lined and the bolsters are provided at their side faces with wear plates, suitable spaces being provided to afford the necessary play or rocking movement of the rear runners. The reduced portions 24 of the rear bolster are retained in the recesses 23 by metallic straps 25, which 35 secure the rear runners to the rear bolster. The metallic straps, which are approximately U-shaped, are composed of horizontal top portions and front and rear inclined portions which bind the top and front and rear edges or faces of the central projecting portions of the rear runners. The rear runners are curved upwardly in advance of the central projecting portions 22,

and the front terminals of the rear runners are connected with the main frame by links 26 and with each other by a transverse rod 27. The links 26, which are provided with bifurcated or forked rear ends 28 to straddle the front terminals of the rear runners, are pivoted to the same by the transverse rod 27, which pierces the forked rear terminals of the links and the front ends of the rear runners, as clearly indicated in Fig. 2 of the drawing. The transverse rod forms a brace and firmly connects the rear runners with each other. The longitudinal links extend upwardly and forwardly from the rear runners at an inclination, and their front terminals are loosely connected with the main frame by loops 29, which are linked into eyes 30 of the main frame. The eyes 30 depend from the main frame at opposite sides thereof and the loops 29, which are 40 preferably formed by staples, permit a limited movement of the links, which are adapted to accommodate themselves to the rocking movement of the rear runners, afforded by the connection between the same 45 and the rear bolster.

The rear runners carry longitudinally disposed propeller frames 31, pivotally connected at their front ends with the upwardly projecting portions 22 of the rear runners 50 by transverse shafts 32 and carrying at their rear portions transverse shafts or axles 33, on which are mounted propelling wheels 34, yieldably maintained by springs 35 in engagement with the surface over which the 55 sleigh is traveling. The propeller frames or supports, which may be of any preferred construction, are composed of spaced side bars and are adapted to swing upwardly and downwardly on the front pivot shafts 32, and they are guided in their upward and downward movement by spaced arms 36, arranged in pairs and depending from the rear portion of the main frame. The guiding arms are located at a point intermediate 60 of the ends of the rear raised portion of the main frame and fit against the side bars of the propeller frames near the centers thereof, and they are suitably braced, as shown. The main frame is preferably provided at 65 its rear portion with right angle bends, which upwardly offset the rear portion of the main frame from the horizontal plane of the body portion of the same to provide a lower space sufficient to accommodate the 70 propelling mechanism. The propelling wheels consist of central hub portions and tapered spokes 37, extending radially from the central hub portions of the propelling wheels and adapted to operate effectively on 75 loose wet snow, as well as on hard, packed surfaces. The springs 35, which may be of any preferred construction, preferably consist of upper and lower sides and a connecting spring coil 38, the sides or arms being 80

fastened or otherwise secured to the main frame and to the rear portions of the side bars of the pivoted propeller frames. These springs are designed to be of sufficient strength to maintain the propelling wheels in engagement with snow covered surfaces with the desired pressure to secure a positive and effective operation of the propelling mechanism. The propeller frames are adjustable independently of each other by means of wire cables 39 and 40, or other suitable flexible connections, and are connected at their rear ends with the propeller frames by approximately inverted U-shaped yokes 41 having central eyes 42 for the attachment of the said cables, and provided at opposite sides with openings through which pass the rear shafts or axles of the propelling wheels. The sides of the yokes 41 are straight and they are arranged between the side bars of the propeller frames and are fitted against the inner faces of the said bars. The cables 39 and 40, which have their rear portions located at opposite sides of the sleigh, extend upwardly from the propeller frames to and pass over grooved guide pulleys 43, and they are guided at their rear portions longitudinally of the main frame by pulleys 44 and 45. The cable 39, which has its rear portion located at the left hand side of the sleigh, extends across the latter, the right hand side being guided by an intermediate pulley 46, and the front portions of the cables 39 and 40 pass over grooved pulleys 47 and have their front terminals attached to drums 48 of adjusting levers 49. The drums 48, which are adapted to have the front terminal portions of the cables 39 and 40 partially wound on them, are mounted on a transverse shaft 50 and the operating levers 49 are secured in their adjustment by pawls or dogs 51, connected with latch levers and arranged to engage toothed segments 52. When it is desired to turn the sleigh to the right, the propelling wheels at the right hand side of the sleigh are lifted, and the steering mechanism operated to turn the front runners and the rod, and when the sleigh is to be turned to the left, the propelling wheels at the left hand side of the sleigh are raised and the steering mechanism correspondingly operated. By mounting the opposite pairs of propelling wheels independently of each other, at the rear end of the sleigh, the latter is enabled to make a quick, sharp turn and may be easily and accurately guided by the steering mechanism.

The sleigh is designed to be equipped with an internal combustion engine or other suitable motor 53, as indicated in dotted lines in Fig. 2 of the drawings. The engine 53 is connected with a longitudinal power shaft 54 which transmits motion through a differential gearing 55 of any preferred con-

struction to a divided transverse shaft 56, extending across the sleigh and connected at the outer terminals of its sections with the pivoted shafts 32 by sprocket or other suitable gearing. The sprocket gearing comprises substantially vertical sprocket chains 57 and upper and lower sprocket wheels 58 and 59, mounted respectively on the divided transverse shaft 56 and the pivoted shafts 32, and meshing with the sprocket chains 57. Motion is transmitted from the pivoted shafts 32 to the rear shafts or axles 33 of the propelling wheels by longitudinally disposed sprocket gearing comprising sprocket chains 60 and front and rear sprocket wheels 61 and 62, mounted respectively on the front pivoted shafts and the rear shafts or axles. Any other suitable gearing may, of course, be employed for transmitting motion from the pivoted shafts to the propelling wheels, and the sprocket wheels 59 and 61, which are carried by the pivoted shafts, are located at the inner and outer sides of the rear runners. The sleigh is designed to be also equipped with the usual speed controlling means for enabling the propelling wheels to be rotated at different speeds and in either a forward or reverse direction. As this mechanism is of the usual construction customarily employed on automobiles, illustration thereof is deemed unnecessary.

The sleigh is equipped with a brake consisting of a dog 63 mounted between the rear portions of a pair of oscillatory bars 64, which are pivoted at their front ends between spaced depending lugs 65 of a bracket 66. The front ends of the bars 64 are pierced by a transverse pin 67, which is suitably secured in the lugs 65 of the bracket 66. The bracket is preferably secured beneath the central portion of the rear bolster of the sleigh, and the bars 64, which are spaced apart at their front ends, are provided near their rear ends with recesses 67 formed in the inner faces of the bars 64 and receiving the dog 63. The dog 63, which has a tapered lower portion, extends below the bars 64 and is provided at its upper end with an eye or opening in which is secured the rear end of a cable 68, or other suitable flexible connection, extending upwardly from the said dog and guided by suitable pulleys and connected at its front end with a suitable operating lever 69, constructed similar to the levers 49 and equipped with a pawl or dog 70 for engaging a toothed segment 71. The dog of the brake is adapted to be forced into engagement with the snow by a pair of springs 72, constructed similar to the said springs 35 and secured to the main frame and to the upper faces of the bars 64. When it is desired to stop the sleigh, the power may be shut off or the propelling wheels may be lifted clear of the surface, and the brake released to cause the

5 springs 72 to force the dog into engagement with the snow covered surface. This will bring the sleigh to a quick stop. The brake, of course, may be equipped with one or more 10 of the dogs to adapt it for vehicles of different kinds and sizes. No claim is made in the present application to the brake.

15 In practice, the gearing of the propelling mechanism will be housed within a suitable 10 casing to prevent the snow from clogging or otherwise interfering with the operation of the said gearing, and the rear runners are preferably equipped with snow plows consisting of blades 73 secured to and extending laterally from opposite sides of the central upwardly projecting portions of the rear runners. The blades, which are set at an angle to the side faces of the rear runners, have tapered upper portions 74, which 20 are curved transversely. The snow plows are adapted to clear a path for the propelling mechanism, and the blades 73 operate to throw the snow outwardly from the rear runners.

25 What is claimed is:

1. A motor propelled vehicle including a main frame, rocking rear runners, propeller frames pivotally mounted on and carried by and movable independently of the rear runners, a motor mounted on the main frame, propelling wheels mounted on the propeller frames, and gearing for connecting the motor with the propelling wheels.

2. A motor propelled vehicle including a 35 main frame, rocking rear runners, propeller frames provided with spaced side bars located at opposite sides of the said runners and pivoted to and carried by and movable independently of the same, guiding arms arranged in pairs and depending from the main frame at the inner and outer sides of the runners and receiving and guiding the propeller frames, and means for rotating the propeller wheels.

45 3. A motor propelled vehicle including a main frame, a rocking rear runner, a propeller frame pivotally mounted on and carried by the rear runner, said propeller frame being also movable independently of the said runner, a motor mounted on the main frame, a propelling device mounted on the propeller frame, and gearing for connecting the motor with the propelling device.

55 4. A motor propelled vehicle including a main frame, runners, propeller frames pivotally mounted on the runners, propelling wheels carried by the propeller frames, and guides depending from the main frame and receiving and guiding the propeller frames.

60 5. A motor propelled vehicle including a main frame, runners, propeller frames pivotally mounted on the runners and movable upwardly and downwardly, propelling wheels carried by the propeller frames, and 65 springs connected with the main frame and

the propeller frames for urging the propelling wheels downwardly.

6. A motor propelled vehicle including a main frame, runners, propeller frames pivotally mounted on the runners and movable upwardly and downwardly, propelling wheels carried by the propeller frames, guiding means for the propeller frames carried by the main frame, springs connected with the main frame and the propeller frames for urging the same downwardly, and operating means mounted on the main frame and connected with the propeller frames for raising the same.

7. A motor propelled vehicle including 80 rocking runners, propeller frames having spaced side bars arranged at opposite sides of the runners, transverse shafts pivoting the side bars to the runners, propelling wheels mounted on the propeller frames, 85 gearing connecting the propelling wheels with the front shafts, and power driven means carried by the vehicle for rotating the front shafts.

8. A motor propelled vehicle including 90 runners, propelling wheels connected with and carried by the runners and blades secured to and extending laterally from the runners at a point in advance of the propelling wheels.

9. A motor propelled vehicle including 95 runners, propeller frames pivotally connected with the runners and movable upwardly and downwardly, propelling wheels mounted on and carried by the propeller frames, gearing for rotating the propelling wheels, and snow plow blades secured to the inner and outer faces of the runners at a point in advance of the propeller frames and extending laterally beyond the same.

10. A motor propelled vehicle including 100 runners, propeller frames provided with spaced side bars, front shafts pivoting the side bars to the runners, rear shafts carried by the propeller frames, propelling wheels 110 arranged in pairs and mounted on the rear shafts at the sides of the propelling frames, gearing connecting the said shafts, yoke arranged between the side bars of the propeller frames and connected with the rear 115 shafts, and operating means having flexible connections extending to and connected with the said yokes.

11. A motor propelled vehicle including 120 a main frame, rear runners, propeller frames carried by the rear runners, propelling wheels mounted on the propeller frames and located at the rear portions of the runners, and longitudinally disposed links connecting the front ends of the rear 125 runners with the main frame.

12. A motor propelled vehicle including a main frame, rear runners, propeller frames carried by the rear runners, propelling wheels mounted on the propeller frames and 130

located at the rear portions of the runners, inclined links connected at their upper ends with the main frame, and a transverse brace connecting the front ends of the rear runners and pivoting the lower ends of the links to the same.

In testimony that I claim the foregoing

as my own, I have hereto affixed my signature in the presence of two witnesses.

JOSEPH SONNENBERG.
